(57) **CLAIM**

The ornamental design for a suspended luminaire, as shown and described.

DESCRIPTION

FIG. 1 is a bottom perspective view of the suspended luminaire of the present invention;

FIG. 2 is a top perspective view of the suspended luminaire of FIG. 1;

FIG. 3 is a front view of the suspended luminaire of FIG. 1; FIG. 4 is a bottom view of the suspended luminaire of FIG. 1; FIG. 5 is an enlarged left side view, the right side view being a mirror image, it is not shown; and,

FIG. 6 is a top view of the suspended luminaire of FIG. 1.

The broken lines showing environmental structure are for illustrative purposes only and form no part of the claimed design.

The suspended luminaire is shown broken away with a bracket and a separation to indicate no specific length is claimed.
